EDUARD F. H. H. LAUCKERT, OF LONDON, ENGLAND, ASSIGNOR TO SIEMENS BROTHERS & CO., LIMITED, OF SAME PLACE.

SWITCH FOR VARYING ELECTRICAL RESISTANCE.

SPECIFICATION forming part of Letters Patent No. 608,878, dated August 9, 1898.

Application filed November 29, 1897. Serial No. 660,147. (No model.) Patented in England May 2, 1895, No. 8,727.

To all whom it may concern:

Be it known that I, EDUARD FRIEDRICH HERMANN HEINRICH LAUCKERT, of 12 Queen Anne's Gate, Westminster, London, in the county of Middlesex, England, have invented certain new and useful Improvements in Switches for Varying Electrical Resistance, (for which I have obtained a patent in England, No. 8,727, dated May 2, 1895,) of which

the following is a specification.

For many purposes, especially for the starting and regulating of motors, it is necessary to vary the resistance in an electric circuit, and in order to effect this gradually there are arranged in a switch a considerable number of contact plates or segments connected through successive resistances and a brush or rubber which is moved over these so as to introduce or cut out these resistances step by step.

This invention relates to the construction of resistance-switches and their brushes in such a manner that in order to provide for a given number of steps the number of contact plates or segments and of the resistances and their connections may be considerably reduced, or, in other words, that a given number of plates or segments, resistances, and connections may serve for a considerably-greater number of steps. For this purpose instead of one brush

two or more brushes insulated from each other are employed. One of these, which may be termed the "leading" brush, as it is moved over the contact plates or segments brings them successively into direct connection with the circuit. The second brush as it is moved along with the first brings the successive plates or segments into connection with a bar or segment which is connected not directly but through a certain resistance to the circuit.

In like manner there may be a third brush moving along with the others and connecting the successive plates or segments to another bar or segment connected to the circuit through another resistance. The successive contact plates or segments may be so spaced that only one of the brushes is on one of them at a time. When the first brush is on, all the resistance up to that particular plate or segment is in circuit. When the second brush is

on, an additional resistance is included, and when the third brush is on a still greater resistance is included. In this way the added resistance due to the step from one contact to the next is divided into three steps, or a certain number of contact-plates and resistances is by the addition of the two brushes and their two resistances rendered available for thrice the number of steps.

According to a modified arrangement the leading brush is connected to each of the others through a resistance. The contact plates or segments are so arranged that one, two, or all of the brushes may be on one plate or segment at a time or that one, two, or more may be on one plate, while of the others one may be over the gap between the plates and the others on the next plate. By the parallel routes thus provided for the current the step from one resistance to the next in order is subdivided.

In cases where the successive resistances between the plates or segments vary it may be of advantage also to vary the resistances between the leading brush and the others. This can be done by providing each of the brushes with a second contact sliding over a separate conducting bar or segment, which may be divided into sections connected to each other through suitable resistances.

Figure 1 is a diagram showing a series of resistances and contact-segments constituting a switch with two brushes 1 and 2, insulated from each other, except that they bear on conducting-bars 10 and 13, connected together through a resistance 4. When the brushes are in position A, the current to be varied in the circuit 8 passes at 9 to the first segment 6 through brush 1 and bar 10 back to 8. By moving the brushes to a position such as B, when the brushes are on two segments, the current, entering at 9 and passing through a number of resistances 7 to the point 11, divides into two parts, one passing through resistance 12 and brush 1 to the bar 10 and the other part passing by brush 2, bar 13, and resistance 4 to bar 10, where it joins the first part, both returning together to 8. By moving the brushes to such a position as C, where brush 2 is over the interval between two segments, the cir-

cuit-bar 13 and resistance 4 is cut off. At position D of the brushes the current, after having passed through all resistances 7, passes through the brush 2, bar 13, resistance 4, and bar 10 to 8.

Fig. 2 is a diagram of a switch with three brushes. In position A the current passing by 6, 1, and 10 encounters none of the resistances. In position B brush 1 is on one segment and brushes 2 and 3 on the preceding segment, putting three resistances 4, 5, and 7 in parallel. In position C brush 1 is on one segment, brush 2 is over an interval, and brush 3 is on the preceding segment. In this case 15 resistance 4 is disconnected and only 5 and 7 are in parallel. In position D the brushes 1 and 2 are on one segment and brush 3 is over a gap, the resistance 7 being only in circuit.

Figs. 3 and 4 are diagrams of switches in 20 which the resistance-steps 7 are increased as more resistance is introduced into the circuit. The resistances between the brushes must also increase, and therefore the conducting-bar 13 in Fig. 3 and the bars 14 and 15 in Fig. 25 4 are made each in two parts, with resistances 16 connecting the parts, which in positions of the brushes at and beyond G are added to the resistances 4 and 5.

In Figs. 1, 2, 3, and 4 the contacts and bar 30 30 are shown arranged for rectilineally-sliding brushes. They may be conveniently arranged for brushes moving circularly.

Fig. 5 is a section, and Fig. 6 a plan, of such a circular switch having thirteen contact-segments S, with interposed resistances T, which 35 with a single brush in the usual way would give twelve steps; but by employing a second brush B and the inner segments C, corresponding to divided bars, such as 13 or 14 in 40 Fig. 4, the steps are increased to twenty-five. The brush A is in connection through the axis with terminal D. The brush B moves over the conducting-segments C, one segment of which is connected to brush A through 45 a resistance E. There are three intervals between the segments C, bridged by resistances F G H, so that as the back part of brush B slides over the segments the resistances F G H are automatically added to the resistance 50 E. When the brushes are in the position shown in Fig. 6, all the resistances T, E, F, G, and H are in circuit. The current enters at K, passes through the twelve resistances T to brush B and the segment C, then through

segment C' and resistances H, G, F, and E 55 to the axis and terminal D.

Having thus described the nature of this invention and the best means I know for carrying the same into practical effect, I claim—

1. In a switch for varying electrical resistance, the combination with a series of conducting-segments connected by successive resistances, of two or more brushes connected to move together but insulated from each other and electrically connected through a 65 resistance, and designed to be moved over said conducting-segments and in contact therewith, one or more of said brushes being of a width to lie over the interval between two segments and out of contact with either, 70 substantially as described.

2. In a switch for varying electrical resistance, the combination with a series of conducting-segments connected by successive resistances, of two or more conducting-bars 75 connected by resistances, and two or more brushes connected to but insulated from each other and bearing respectively on said conducting-bars, said brushes being designed to be moved over said conducting-segments and 80 in contact therewith and one or more of said brushes being of a width to lie over the interval between two segments and out of contact with either, substantially as described.

3. In a switch for varying electrical resistance, the combination with a series of conducting-segments connected by successive resistances, of two or more conducting-bars connected by resistances, one or more of said bars being formed in two parts connected by 90 a resistance, and two or more brushes connected to but insulated from each other and bearing respectively on said conducting-bars, said brushes being designed to be moved over said conducting-segments and in contact 95 therewith and one or more of said brushes being of a width to lie over the interval between two segments and out of contact with either, substantially as described.

In testimony whereof I have signed my 100 name to this specification, in the presence of two subscribing witnesses, this 16th day of November, A. D. 1897.

EDUARD F. H. H. LAUCKERT.
